SEPARABLE FASTENER

Otto Ulbricht, Birkwitz-on-the-Elbe, Germany

Application May 3, 1935, Serial No. 19,677
In Germany May 2, 1934

5 Claims. (Cl. 24—205)

This invention relates to separable fasteners. In the known types of separable fasteners comprising fastening elements made of metal or artificial materials the individual elements are firmly attached to the stringers or bands, so that fasteners can be made only in definite measured lengths which often are not suited for special purposes. Furthermore, variegated fasteners made from artificial masses, besides being obtainable at present only in certain lengths, depend for their color scheme and general arrangement entirely upon the taste of their manufacturers, and the maintenance of an ample stock thereof affording a wide selection involves a considerable, and frequently unbearable, outlay on the part of both manufacturers and distributors.

The invention eliminates these drawbacks by providing a separable fastener, the fastening elements of which, with the exception of an initial member and an end member, loosely ride on the stringer instead of being firmly secured thereto.

The fastener according to the invention affords the advantage that the two interlocking elements meet each other smoothly, so that the frequent obstructions known to all users of the existing types of separable fasteners are eliminated, even if the latter form a curve instead of a straight line. Besides, the invention makes it possible for users to assemble a separable fastener from individual units according to their taste as to the color scheme and their requirements as to length.

The invention attains its object by providing the elements to be connected with the stringer with channels and slots proceeding therefrom and arranging the channels on the roll edge of the stringer or band and placing the body of the latter between the slots. Lateral withdrawal of the elements is effectively prevented, since the channels correspond in diameter to the reinforced edge of the stringer and the slots to the thickness thereof.

By way of example, one form of the invention is illustrated in the accompanying drawing, in which Figure 1 is a view of a finished separable fastener; Fig. 2, a top view of a fastening element; Fig. 3, a rear view of an initial member; Fig. 4, a top view of an initial member with the clamping member opened; Fig. 4a is a section on the line C—D, of Fig. 3, and shows the lower half of the initial member; Fig. 4b, a top view of the initial member placed on the stringers, with the clamping member half closed whose teeth engage the reinforced edge of the string-

ers; Fig. 5, a lateral view of an end compensating and stop member with the clamping member fully turned up; Fig. 6, a side view of a fastening element; Fig. 7, a sectional view of a fastening element in the direction of the line A—B, of Fig. 2; and Fig. 8, a top view of a fastening element.

Referring to the drawing, 1 designates the two stringers or bands of fabric to be sewn to the article concerned, which on the sides facing each other have a reinforced edge 2. The individually attachable fastening elements may have any desired shape and are fitted with the channels 3 and, branching off therefrom, the slots 4 which are open on the side and smaller in width than the diameter of the channels 3.

In a single row construction of the fastener the heads of the elements meeting each other are of corresponding length and provided with notches 5, so that after engagement of the elements the opposite reinforced edge is inserted in the notches 5 and the sides 6 insure good guiding of the stringer.

The initial member 7 as shown in Figs. 1, 3, 4 is provided with two channels 10, each of which opens laterally into a slot 11. The clamping member 8 fitting snugly into a recess 12 and having comb-like holding teeth 13 serves for loosening the initial member 7 so as to permit proper arrangement and spacing of the fastening elements.

The fastening elements shown in Figs. 6, 7, 8 have a hemispherical shape or other suitable form and possess a cavity 14 corresponding to their shape. They are further provided with a camlike projection 15 extending into a lower stop 16 and an upper one 17 and with an opening 5, 6 disposed oppositely the cavity 14. The channel 10 and the slot 11 are intended to facilitate the arrangement of the fastening elements on the reinforced edge 2 so that they are loosely seated thereon.

The end compensating and stop members 9, as shown in Figs. 1 and 5, serve for compensating and finishing the fastener and, in principle, are constructed like the initial members 7, with the difference, however, that the channel 10 and the slot 11 are disposed on one side only, that is, where the camlike projection 15 or the other projection 19 with the stops 17 of the initial member 7 are located, as indicated in Fig. 4. The clamping member 8 having its teeth 13 in the recess 20, in which it is rotatably disposed with its shaft 21, serves again for securing the end 55

members 8 to the reinforced edge 2 so as to be readily detachable.

In a two row construction the notches 5 are dispensed with and the heads of the elements shortened to the extent of the length of the sides 6.

I claim:—

1. Separable fastener, comprising, in combination, stringers each having a reinforced edge, ext-
20 changeable and fixable initial and end members on the reinforced edges of said stringers and a plurality of detachable fastening elements loosely disposed on the reinforced edges of said stringers between said initial and end members, said 15 fastening elements being provided with channels and slots laterally extending from said channels and open on the side for selectively arranging said elements on said stringers.

2. Separable fastener according to claim 1, 20 wherein the reinforced edge of the stringers is inserted in the channels of the fastening elements and the body portion of the stringers in the slots thereof.

3. Separable fastener according to claim 1, wherein the width of the slots of the fastening elements is smaller than the diameter of the channels.

4. Separable fastener according to claim 1, 5 wherein the initial members are recessed and each fitted with two channels laterally opening into slots and a toothed clamping member is provided adapted to be turned up and down and to engage said recess for detachably fastening 10 the initial members to the reinforced edge and facilitating proper arrangement and spacing of the fastening elements relative to one another.

5. Separable fastener according to claim 1, 15 wherein the end members are recessed and each fitted with a channel and slot on one side and a toothed clamping member is provided adapted to be turned up and down and to engage said recess for detachably securing the end members to the reinforced edge.

OTTO ULRICH.
